Primary Examiner — Austin Murphy(74) *Attorney, Agent, or Firm* — Howard Russell(57) **CLAIM**

I claim the ornamental design for a USB flash drive holder, as shown.

DESCRIPTION

FIG. 1 is a front perspective view of a USB flash drive holder with a cap portion in an open position;

FIG. 2 is a front perspective view thereof with the cap portion in a closed position;

FIG. 3 is a front elevation view of the USB flash drive holder as shown in FIG. 2;

FIG. 4 is a rear elevation view of the USB flash drive holder as shown in FIG. 2;

FIG. 5 is a top plan view of the USB flash drive holder as shown in FIG. 2;

FIG. 6 is a bottom plan view of the USB flash drive holder as shown in FIG. 2;

FIG. 7 is a left side elevation view of the USB flash drive holder as shown in FIG. 2; and,

FIG. 8 is a right side elevation view of the USB flash drive holder as shown in FIG. 2.
